UNITED STATES PATENT OFFICE

JOHN M. VAN SPLUNTER, OF GRAND RAPIDS, MICHIGAN

ELECTRICAL LOCK SWITCH

Application filed July 5, 1928. Serial No. 290,382.

This invention relates to electrical lock switches and has among its objects a lock switch suitable for large-power high-voltage operation provided with an improved lock 5 that is simple and economical in construction and particularly adapted for blade-type switches.

The forces exerted in switches used in high-tension circuits are very large, particularly 10 under short-circuit conditions. Accordingly, a very great duty is imposed on the locks used in such locking switches and it is a considerable problem to provide a simple lock capable of withstanding the large forces to 15 which it is subjected while at the same time retaining simplicity of construction and mounting in the restricted place at the end of the blade.

The lock embodied in the switch of my 20 invention is extremely simple and all the parts of it may be made of sheet metal. All the elements of the lock are arranged to be mounted in operative position in the narrow space corresponding to the width of the 25 switch blade itself without requiring special cast housings of the type generally used heretofore.

The objects of the invention will be best understood from the following description of 30 exemplifications thereof, reference being had to the accompanying drawings wherein.

Fig. 1 is a view of a double throw switch embodying my invention;

Fig. 2 is a vertical sectional view through 35 the switch lock mechanism of Fig. 1;

Fig. 3 is a vertical sectional view of the mechanism along the line 3—3 of Fig. 2;

Fig. 4 is a view similar to Fig. 2 along the line 4—4 of Fig. 2;

Fig. 5 is an elevational view of a single throw switch embodying the invention, and

Fig. 6 is a view similar to Fig. 2 of the lock used on the single throw switch of Fig. 5.

Figs. 1 to 4 illustrate an embodiment of 45 the invention in a double-throw type of switch. It comprises a switch blade 1 which is pivotally mounted on a central post 2 and arranged to be brought into engagement with either one of two stationary contact members 3, 4 made of resilient jaws adapted

to engage the opposite sides of the blade 1. Each of the stationary contact members 3 and 4 has on the outer side, directly underneath the space adapted to receive the blade, a catch member 5 in the form of a hook for 55 engagement with a corresponding hook of a lock 6 mounted on the end of the switch blade.

The construction of the lock 6 is shown in detail in Figs. 2 to 4. It comprises a pair of flat side plates 7 having their lower 60 ends secured to opposite sides of the end of the blade 1, by means of rivets 8, for instance, the two side plates defining a narrow, substantially rectangular, space 9 of the thickness of the blade. Within this narrow 65 rectangular space 9 are mounted the several elements of the lock mechanism. This mechanism comprises an actuating lever 11 having a central portion 12 pivotally mounted on a pivot pin 13 secured between the opposite 70 side plates 7; an outwardly extending handle or grip portion 14 provided, for instance, with a suitable perforation 15 for engagement with a hook rod to close or open the switch; and an inwardly extending cam lever 16 disposed in the space 9 between the side plates 7. On both sides of the portion of 75 the lever 11 extending between the side plates 7 there are mounted two hook levers 17, each hook lever having on one end a hook 17a 80 adapted to engage the hook catch 5 on the stationary contact members. The other end of each hook arm 17 is pivotally mounted on a pin 18 likewise secured between the opposite side plates 7 at the blade end. Each 85 hook lever 17 has a laterally projecting arm 19 extending towards the end of the blade 1, the end portion of that arm constituting a stop 20 for limiting the inward movement of the hook lever 17. The two arms 17 and 19 of each lever thus form a bell crank. The two hook levers 17 are normally forced to closed position as shown in Fig. 2 by a coiled 90 tension spring 22 having its ends shaped into wire hooks 23 fitting into narrow slots 24 cut along the middle line of the lever arms 19, the wire hooks engaging pins 25 transversely extending across said slots and held in said arms.

The inner sides of the two hook lever arms 100

19 constitute cam surfaces 27 bearing against the two sides of the cam member 16 of the actuating lever. These cam surfaces 27 and the cooperating cam lever portions 16 are so shaped that upon rocking the lever 11 around its pivot 12 in one side or another the cam lever 16 will swing one or the other of the hook levers 17 to open position. Through the arrangement of the elements of the mechanism in the way described above, pull on the actuating lever 11 in a direction tending to open the switch will always lift the latch lever 17 which holds the switch locked out of engagement with its cooperating catch hook so that by a single movement of the actuating lever 11 the lock is released and the switch opened.

The central portion 12 of the actuating lever has an outer contour of such shape that said lever is free to swing around its pivot 13 to a sufficient extent to bring one or the other of the hook levers 17 out of engagement with its cooperating catch member 25, the body of the hook lever on the opposite side serving as a stop for the further movement of the actuating lever 11.

The three levers have substantially the full thickness of the blade and fit into the narrow space 9 bounded by the two side plates 7. All these parts may be made of sheet metal by stamping and may be readily assembled through very simple operations. The several pivoting pins 13 and 18 serve also as spacers, having their ends somewhat reduced to form shoulders for holding the side plates 7 apart the required distance for securing free and unobstructed movement of the lock elements. The ends of these pins serve as rivets holding the side plates 7 in fixed position. Since the three pivoting pins 13, 18 are mounted near the upper edge of the side plates, the structure does not require any additional reinforcement and great rigidity is thus secured with the utmost economy of material and working operations. By the arrangement described the cam arm 19 on each hook lever 17 is used for performing three functions, namely, to act as a stop for limiting the inward movement of the hook lever, as a cam surface for bringing the hook lever to open position, and as the anchoring point for the spring which forces the lever to closed position, thereby contributing greatly to the simplicity of the entire structure.

The arrangement of the several lever arms is such that through a relatively small angular movement of the actuating lever 11 a relatively large movement of the hook levers 17 is obtained, the active length of the cam arms 19 being relatively short compared to the length of the hook arm 18. By anchoring the tension spring 22 near the end of the cam levers 19, while causing the cam member 16 to act on a shorter arm, a relatively

small spring is sufficient for holding the hook levers 17 firmly in closed position.

The lock of my invention is also suitable for use on single throw switches such as shown in Fig. 5. In the latter arrangement, the lock, as shown in Fig. 6, is provided only with a single hook lever 17 arranged similar to the construction shown in Figs. 2 to 4. The other hook lever on the opposite side is replaced by a spacing member 31 which may have the form of the hook lever with the hook portion extending outside of the contour of the side plates 7 cut off.

Other constructions embodying the ideas underlying the exemplifications of my invention described above will suggest themselves to those skilled in the art. It is accordingly desired that the claims be given a broad construction commensurate with the scope of the invention within the art.

I claim:

1. In an electrical switch, a pair of posts, a switch blade pivoted on one post, a catch on the other post and a lock on said blade adapted to engage said catch, said lock comprising a pair of side plates disposed on opposite sides of said blade and secured thereto, a hook lever pivotally mounted between said plates, said hook lever having a hook arm extending outside the space between said plates and adapted to engage said catch and a right angularly disposed cam arm extending between said plates and projecting against said blade to form a stop, a tension spring engaging the end of said cam arm to force said hook arm to closed position, an actuating lever pivotally mounted back of said hook lever, said actuating lever having a grip portion projecting outside the space between said plates and a cam lever extending inside said space for engagement with the inner surface of said cam arm for actuating the same to open position.

2. In an electrical lock switch, a pivotally mounted switch blade, a stationary contact member for engaging said switch blade, said stationary member having a pair of jaws for engaging said blade on both sides thereof and a catch disposed directly underneath the space adapted to be occupied by said blade, and a lock on said blade for engaging said catch, said lock comprising a pair of side plates secured on opposite sides of said blade to form a narrow housing space therebetween, a pair of pins secured near the free end of said side plates to hold the same in fixed spaced relation, a hook lever pivoted on one of said pins disposed on the side adjacent said catch, an actuating lever pivotally mounted on the pin back of said first mentioned pin, said hook lever having a cam arm extending in the direction from its associated pivot pin against said blade, said actuating lever extending from its pivot pin in the direction toward said blade and ar-

ranged to act upon said cam arm, and a tension spring anchored in the space between said side plates adjacent the said blade and engaging the end of said cam arm to hold the same in closed position.

5. In an electrical switch, a pivotally mounted blade, a stationary contact member adapted to be engaged by said blade, a hook catch on said stationary contact member, and a lock on the end of said blade for engagement with said hook catch, said lock comprising a supporting member extending from said blade, a bell crank lever pivotally mounted on said supporting member, one arm of said bell crank lever having a hook for engagement with said catch, the other arm of said bell crank lever projecting against said blade and having a cam surface on the side away from said hook, an actuating lever pivotally mounted on said supporting member adjacent to the pivoting point of said bell crank lever on the side opposite said hook arm, said actuating lever having a cam arm in engagement with said cam surface, and a spring acting on the end of said cam surface arm for forcing said hook lever into closed position.

4. In an electrical switch, a pivotally mounted switch blade, a pair of stationary contact members on opposite sides of said blade arranged to be engaged thereby, a catch on each of said stationary contact members, and a lock on the end of said blade for engagement with either one of said catches, said lock comprising a supporting member extending from said blade, a pair of bell crank levers pivotally mounted on said supporting member, said bell crank levers having a pair of hook members projecting away from each other and a pair of cam members extending substantially in the same direction against said blade, said cam members having cam surfaces on the sides opposing each other, and an actuating lever pivotally mounted between said bell crank levers, said actuating lever having a cam arm engaging the opposite cam surfaces of said cam members, and spring means acting on said cam members for holding said hook members in closed position.

5. In an electrical switch, a pivotally mounted switch blade, a pair of stationary contact members on opposite sides of said blade arranged to be engaged thereby, a catch on each of said stationary contact members, and a lock on the end of said blade for engagement with either one of said catches, said lock comprising a supporting member extending from said blade, a pair of bell crank levers pivotally mounted on said supporting member, said bell crank levers having a pair of hook members projecting away from each other and a pair of cam members extending substantially in the same direction against said blade, said cam members

having cam surfaces on the sides opposing each other, and an actuating lever pivotally mounted between said bell crank levers, said actuating lever having a cam arm engaging the opposite cam surfaces of said cam members, and a tension spring connecting the ends of said cam members to hold said hook members in closed position.

6. In a double-throw switch, a pair of stationary contact members, a pivotally mounted blade adapted to be thrown in contact with either one of said contact members, a catch on each of said contact members, a double-throw lock on the end of said blade for engagement with either of said catches for locking said blade, said lock comprising a pair of plates secured to the end of said blade on opposite sides thereof to form a housing space therebetween, a pair of bell crank levers pivotally mounted within said space near the outer ends thereof, each of said levers having a hook arm projecting outside of said housing space in the direction away from said blade for engagement with one of said catches, and a cam arm extending in the direction toward said blade, each of said cam arms having a cam surface on the side facing the cam arm of the other lever, and an actuating lever pivotally mounted between said side plates in the space between said levers, said actuating lever having an actuating member projecting outside of said housing space, and a cam member projecting from the pivoting point into the space between the cam surfaces of said cam arms for engagement therewith, and a tension spring connecting the free ends of said cam arms.

7. In a double-throw lock switch, a pair of stationary contact members, a pivotally mounted switch blade for engagement with either of said contact members, a catch on each of said contact members, a lock on the end of said blade for engagement with either of said catches to lock said blade in closed position, said lock comprising a pair of substantially rectangular plates secured at the end of said blade on opposite sides thereof and extending substantially in the direction of said blade to define a substantially rectangular housing space therebetween, an actuating lever pivotally mounted near the free end of said housing space between said plates substantially in the center thereof for swinging movement in the plane of said blade, said actuating lever having a grip member extending outside said housing space, and a cam member extending inside said housing space in the direction from the pivoting point toward said blade, a pair of bell crank levers pivotally mounted adjacent to the outer edge of said rectangular housing space on opposite sides of the pivoting point of said actuating lever, each of said bell crank levers having a hook arm extending away from said actuating lever for engagement with one of

- said catches, and a cam arm having a cam surface extending into engagement with said cam member, and a tension spring connecting the end points of said cam arms.
8. In a double-throw lock switch, a pair of stationary contact members, a pivotally mounted switch blade for engagement with either of said contact members, a catch on each of said contact members, a lock on the end of said blade for engagement with either of said catches to lock said blade in closed position, said lock comprising a pair of substantially rectangular plates secured at the end of said blade on opposite sides thereof and extending substantially in the direction of said blade to define a substantially rectangular housing space therebetween, an actuating lever pivotally mounted near the free end of said housing space between said plates substantially in the center thereof for swinging movement in the plane of said blade, said actuating lever having a grip member extending outside said housing space, and a cam member extending inside said housing space in the direction from the pivoting point toward said blade, a pair of bell crank levers pivotally mounted adjacent to the outer edge of said rectangular housing space on opposite sides of the pivoting point of said actuating lever, each of said bell crank levers having a hook arm extending away from said actuating lever for engagement with one of said catches, and a cam arm having a cam surface extending into engagement with said cam member, and a tension spring connecting the end points of said cam arms, said bell crank levers and said actuating lever having a thickness corresponding substantially to the thickness of said blade.
9. In an electrical switch, a pair of posts, a switch blade pivotally mounted on one of said posts, a catch on the other of said posts, and a lock on the end of said blade adapted to engage said catch to hold said blade in closed position, said lock comprising a pair of side plates secured to the end of said blade on opposite sides thereof to form a substantially rectangular housing space, a bell crank lever pivotally mounted near the outer end of said housing space for rocking movement in the plane of said blade, said bell crank lever having a hook arm extending away from said blade for engagement with said catch, and a cam arm extending within said housing space and having a cam surface on the side opposite said hook arm, an actuating lever pivotally mounted in said housing space, said actuating lever having a grip member extending from the pivoting point outside said housing space, and a cam member extending from said pivoting point into engagement with the cam surface of said cam arm for swinging said hook lever to open position, and a spring acting on the end

of said cam arm to move said bell crank lever to closed position.

10. In an electrical switch, a pair of posts, a switch blade pivotally mounted on one of said posts, a catch on the other of said posts, and a lock on the end of said blade adapted to engage said catch to hold said blade in closed position, said lock comprising a pair of side plates secured to the end of said blade on opposite sides thereof to form a substantially rectangular housing space, a bell crank lever pivotally mounted near the outer end of said housing space for rocking movement in the plane of said blade, said bell crank lever having a hook arm extending away from said blade for engagement with said catch, and a cam arm extending within said housing space and having a cam surface on the side opposite said hook arm, an actuating lever pivotally mounted in said housing space, said actuating lever having a grip member extending from the pivoting point outside said housing space, and a cam member extending from said pivoting point into engagement with the cam surface of said cam arm for swinging said hook lever to open position, and a spring acting on the end of said cam arm to move said bell crank lever to closed position.

In testimony whereof I have hereunto subscribed my name this 29th day of June, 1928.

JOHN M. VAN SPLUNTER.
